UNITED STATES PATENT OFFICE.

WILHELM B. BRONANDER, OF MONTCLAIR, NEW JERSEY.

FUEL-CONTROL MECHANISM.

Application filed April 1, 1927. Serial No. 180,316.

This invention relates to fuel supply chambers for internal combustion engines.

It is a well known fact that most automobile fires start under the engine hood and are caused by the igniting of the gasoline. Such fires usually center in the carbureter. It is obvious, therefore, that the stoppage of the fuel supply to the fuel supply chamber or carbureter will stop or put out 10 the fire.

Furthermore, it is obvious that an internal combustion engine cannot run without fuel and the stoppage of the fuel supply will render the engine inoperative.

15 This invention has for its salient object to provide a simple and practical fuel control mechanism so constructed and arranged that the fuel supply can be cut off by the engine operator or will be automatically cut off in case of fire.

Further objects of the invention will appear from the following specification taken in connection with the drawings, which form a part of this application, and in which

25 Fig. 1 is a sectional elevation of a carbureter constructed in accordance with the invention;

Fig. 2 is a sectional elevation of a slightly different form of the invention;

30 Fig. 3 is a sectional elevation of a further embodiment of the invention; and

Fig. 4 is a sectional elevation similar to Figs. 2 and 3 but illustrating another type of carbureter having supplemental valve 35 control mechanism thereon.

The invention briefly described consists of a fuel supply chamber for a carbureter having the usual float controlled valve therein and also having supplemental control 40 mechanism adapted to automatically close this valve in case of fire. In the forms of the invention illustrated the supplemental valve control mechanism is carried by the cover of the carbureter float chamber and consists of 45 a spring actuated lever adapted to close the valve. The lever is normally held in inoperative position by means of a fusible link and in case of fire this link melts, permitting the lever to close the valve. If desired, the

50 link may be removed, thus closing the fuel intake to the carbureter and preventing unauthorized persons from operating the car.

Further details of the invention will appear from the following description.

In the embodiment of the invention illustrated in Fig. 1 there is shown a carbureter float chamber 10 having an intake conduit 11 at the bottom thereof communicating with the float chamber through a port 12. The float chamber is connected by a conduit 13 to a fuel nozzle 14 disposed in the intake pipe 15.

A fuel intake control valve 18 controls the passage of fuel from the intake conduit 11 through the port 12 and the valve 18 has a 65 valve stem 19 extending upwardly through an opening 20 in the cover 21 of the float chamber.

A float 22 is slidably mounted on the valve stem 19 and engages a washer 23 secured to the valve stem when the fuel in the float chamber reaches a predetermined level. The float will thereupon close the valve 18, cutting off the supply of fuel to the float chamber.

75 The supplemental wave control or operating mechanism is mounted on the cover 21 and consists of a bell crank lever having one arm 25 extending into a slot 26 formed in the upper end of the valve stem 19, the 80 arm 25 being acted on by a spring 27 positioned in a recess 28 in the cover and pressing upwardly on the arm.

The other arm 30 of the bell crank lever extends upwardly from the lever pivot 31 85 and is engaged by a link 35 of fusible metal, the other end of the link being secured over a hook 36 formed on the cover 21. The fusible link 35 is so dimensioned as to prevent the arm 25 of the bell crank lever from 90 acting on the valve stem 19 under normal conditions. In case of fire, however, the link 35 gives way, permitting the spring 37 to force the arm 25 upwardly, thus effecting the closing of the valve 18 without movement 95 of the float and cutting off the supply of fuel from the fuel supply conduit to the float chamber 10.

100 It is obvious that the car operator can remove the link 35 if desired, thus permitting the spring 37 to close the fuel intake to the carbureter. This will obviously prevent the motor from running and will prevent theft or unauthorized use of the car.

In the embodiment of the invention shown in Fig. 2, the float chamber 10 has a needle valve 40 formed on a valve stem 41 which extends upwardly through the float chamber cover 42.

The stem 41 has mounted thereon a circumferentially grooved collar 43 and a pair of levers 44 are pivoted at 45 to lugs 46 which extend downwardly from the cover 42. The inner ends 47 of the levers are spherical in shape and are disposed in the groove of the collar 43 and the outer ends of the levers are provided with balls 48 adapted to rest on the upper surface of the float 49. The float 49 is slidably mounted on the stem 41.

It will be obvious that when the fuel level in the carburetor rises the float will tilt the levers and at a predetermined fuel level the needle valve 40 will be closed, thus cutting off the fuel supply from the float chamber.

Supplemental means is provided for operating the needle valve independently of the float. This means consists of a lever pivoted at 50 to lugs 51 formed on and extending upwardly from the cover 42. One end 52 of the lever is disposed above the needle valve and the other end of the lever is acted on by a spring 53 and is engaged at its outer end 54 by a fusible link 55, the opposite end of the link being secured to a lug 56 formed on an arm 57 carried by and depending from the cover 42.

The operation of the supplemental valve control means shown in Fig. 2 will be obvious.

In Fig. 3 a slightly different form of carburetor is illustrated. This carburetor has a float chamber 60, a fuel inlet conduit 61, and a needle valve 62 controlling the admission of fuel from the conduit 61 to the chamber 60. A float 65 is positioned in the chamber and engages a lever 66 mounted on a fixed pivot 67 and having its opposite end engaging the needle valve as shown at 68.

The supplemental valve control or operating means in this case consists of a lever mounted on a pivot 70 carried by lugs 71 formed on the cover 72 of the carburetor float chamber. One arm 73 of the lever is disposed above the needle valve 62. Another arm 74 of the lever is acted on by a spring 75 which tends to depress the arm 73. The lever is also provided with an upwardly extending arm 78 engaged at its outer end 79 by a fusible link 80, the opposite end of the link being secured over a lug 81 formed on and extending upwardly from the cover 72. The operation of this embodiment of the invention will be obvious.

In the embodiment of the invention shown in Fig. 4 there is shown a carburetor float chamber 85 having a fuel inlet conduit 86 controlled by a needle valve 87 which in turn is controlled by a float 88 pivoted at 89

to lugs depending from the cover 90. The float has a lug 91 extending upwardly therefrom and engageable with the needle valve 87.

In order to automatically close the needle valve in case of fire an L-shaped arm 95 is mounted in a slot 96 formed in the wall of the float chamber and has one end 97 adapted to engage the float when the arm is moved about its pivot in the slot 96.

The other end 98 of the arm is engaged by a compression spring 99 and is engaged at its outer end by a fusible link 100, the opposite end of the link being secured to a hook 101 carried by a bracket 102 secured to the float chamber as shown at 103. It will be obvious that when the fusible link melts the spring will swing the arm 95 about its pivot in the slot 96 and cause the end 97 of the arm to engage the float 88 and swing the float on its pivot 89 to cause the lug 91 to engage the needle valve 87 and close the fuel intake conduit 86.

From the foregoing specification it will be clear that simple and practical means have been provided for automatically cutting off the supply of fuel from a carburetor in case of fire or for rendering the engine inoperative by cutting off the fuel supply. Furthermore, it is evident that the supplemental valve control means described can be easily and readily attached to carburetors now on the market by simply removing the carburetor covers and substituting therefor a cover having the supplemental valve control device thereon. This change will obviously require a very short time for its accomplishment and the expense will be very slight.

Although certain specific embodiments of the invention have been particularly shown and described, it will be understood that the invention is capable of modification and that changes in the construction and in the arrangement of the various co-operating parts may be made without departing from the spirit or scope of the invention, as expressed in the following claims.

What I claim is:

1. A fuel supply chamber, a fuel supply conduit for said chamber, a valve for controlling the admission of fuel to said chamber from said conduit, a float for operating the valve, a heat responsive means for operating said valve without movement of said float.

2. In a carburetor a float chamber, a float therein, a valve operatively connected to and controlled by said float, a cover for said float chamber, and heat responsive mechanism carried by said cover for operating said valve without movement of the float.

3. In carburetor a float chamber, a float therein, a valve operatively connected to and controlled by said float, a cover for said

float chamber, and heat responsive spring actuated mechanism carried by said cover for operating said valve without movement of the float.

5. 4. A fuel supply chamber, a fuel supply conduit for said chamber, a valve for controlling the admission of fuel to said chamber from said conduit, a float for operating the valve, means operative to close said valve without movement of said float, and heat responsive means for normally holding said means inoperative.

10. 5. A fuel supply chamber, a fuel supply conduit for said chamber, a valve for controlling the admission of fuel to said chamber from said conduits, a float for operating the valve, spring actuated means operative to close said valve without movement of said float, and heat responsive means for 20 normally holding said means inoperative.

25. 6. In a carbureter a float chamber, a float therein, a valve controlled by said float, a cover for said float chamber, and heat responsive mechanism carried by said cover for operating said valve, said mechanism comprising a spring, a lever engaged by said spring and engageable with said valve, and removable means for holding said lever inoperative.

30. 7. In a carbureter a float chamber, a float therein, a valve controlled by said float, a cover for said float chamber, and heat responsive mechanism carried by said cover for operating said valve, said mechanism

comprising a spring, a lever engaged by said spring and engageable with said valve, and fusible means for holding said lever inoperative.

35. 8. A fuel supply chamber, a fuel supply conduit for said chamber, a valve for controlling the admission of fuel to said chamber from said conduit, operating means for said valve, and heat responsive means for operating said valve without movement of said first means.

40. 9. In a carbureter, a fuel supply chamber, a fuel supply conduit for said chamber, a cover for said chamber, a valve in said conduit, means for operating said valve, and other means for operating said valve comprising heat responsive mechanism including a lever carried by said cover.

45. 10. A fuel supply chamber, a fuel supply conduit for said chamber, a valve for controlling the admission of fuel to the chamber from the conduit, a float connected to operate said valve, and heat responsive mechanism for closing said valve, said mechanism including a lever operatively connected to the valve, a spring connected 50 to the lever for actuating the lever to close the valve, and heat responsive means for holding the lever against actuation by said spring.

55. In witness whereof, I have hereunto set 60 my hand this 30th day of March, 1927.

WILHELM B. BRONANDER.
